DATE STAMP OR SIMILAR ARTICLE

Milton L. Albert, Brooklyn, N. Y., assignor to Jos. Freedman & Co. Inc., Brooklyn, N. Y., a corporation of New York

Application July 12, 1954, Serial No. 31,397

Term of patent 14 years

(Cl. D64—10)

The figure is a perspective view of a date stamp embodying my new design.

The side of the date stamp opposite that shown is substantially the same in appearance as the side shown with the exception of the knob element at the top of the handle, which element is rounded on the opposite side.

The opposite end of the date stamp is the same in appearance as the end shown except for the wire element, as illustrated in the drawing figure.

I claim:

The ornamental design for a date stamp or similar article, as shown and described.
